[57] **CLAIM**

The ornamental design for a motortricycle, as shown
and described.

DESCRIPTION

FIG. 1 is a perspective view looking from the left-side
upper direction of the motortricycle;

FIG. 2 is a right-side elevation view of the motortricycle;

FIG. 3 is a left-side elevation view of the motortricycle;

FIG. 4 is a top plan view of the motortricycle;

FIG. 5 is a front elevation view of the motortricycle;

FIG. 6 is a back elevation view of the motortricycle;

FIG. 7 is a perspective view looking from the left-side
upper direction of my design showing the second em-
bodiment of the motortricycle;

FIG. 8 is a left-side elevation view of the second em-
bodiment of the motortricycle;

FIG. 9 is a top plan view of the second embodiment of
the motortricycle; and

FIG. 10 is a back elevation view of the second embodi-
ment of the motortricycle.
